UNITED STATES PATENT OFFICE

138,309

DESIGN FOR A RULER OR SIMILAR ARTICLE

Herbert Austin Aikins, Cleveland Heights, Ohio

Application January 12, 1944, Serial No. 112,217

Term of patent 14 years

(Cl. D52—1)

To all whom it may concern:

Be it known that I, Herbert Austin Aikins, a citizen of the United States and a resident of Cleveland Heights, county of Cuyahoga and State of Ohio, have invented a new, original, and ornamental Design for a Ruler or Similar Article, of which the following is a specification, reference being had to the accompanying drawing, forming a part thereof.

In the drawing—

Fig. 1 is a plan view of a ruler, showing my new design, the article being of conventional thickness; and

Figs. 2 and 3 are enlarged fragmentary detail views of portions of the ruler.

What I claim is:

The ornamental design for a ruler or similar article, substantially as shown and described.

HERBERT AUSTIN AIKINS.
